UNITED STATES PATENT OFFICE

ALFRED C. STEWART, OF LOS ANGELES, CALIFORNIA.

CARBURETING MEANS FOR USE WITH HEAVY FUELS.

Specification of Letters Patent. Patented July 31, 1917.

1,235,255.

Substitute for application Serial No. 799,306, filed November 5, 1913. This application filed August 23, 1915. Serial No. 47,771.

To all whom it may concern:

Be it known that I, ALFRED C. STEWART, a citizen of the United States, residing at Los Angeles, in the county of Los Angeles and State of California, have invented a new and useful Improvement in Carbureting Means for Use with Heavy Fuels, of which the following is a specification.

The main object of the present invention 10 which relates to the same subject-matter as application Serial No. 799,306, filed November 5th, 1913, is to provide for applying heat in an efficient and economical manner to the fuel or mixture supplied by the carbureter for use with internal combustion engines.

A further object of the invention is to provide means for applying such heat to the fuel or charge, more particularly at the 20 time when it is especially needed, viz., when the engine is being started.

Other objects of the invention will appear hereinafter.

The accompanying drawing illustrates an 25 embodiment of the invention, said drawing being a vertical section of the carbureter provided with my improvement.

The carbureter used in connection with my invention may be of any suitable or 30 approved type, comprising, for example, a casing 1, provided with an air inlet 2 and a mixture outlet 3 with a mixing chamber 4 between said inlet and outlet, a fuel chamber 5, and means for controlling the supply 35 of fuel from said fuel chamber to the mixing chamber. As such controlling means form no part of the present invention, they are not herein shown, the drawings showing only the outlet for delivering fuel to 40 the mixture chamber from the fuel chamber.

At any suitable point with relation to the carbureter, for example, directly around the mixing chamber and the outlet 3 thereof, is provided a heating chamber 8, said heating chamber 8 communicating with the mixing chamber or with any suitable portion of the carbureter to receive 45 combustible mixture therefrom by means of a pipe or tube 10. A throttle valve 11 is provided in the outlet 3 of the carbureter, so as to control the supply of mixture through said outlet to the manifold 9 leading to the engine cylinder. A tube or conduit 12 extends from the heating chamber 55 8 to the outlet 3 on the upper side of said

throttle. Said conduit 12 may be provided with a regulating valve 13. An igniting means, for example, a spark plug 14 is provided in the chamber 8 to ignite the charge drawn thereinto.

The tube 12 communicates with the mixture outlet 3 at a point above the seating point of the valve 11, that is, when the valve is closed it lies below the outlet end of the tube.

Spark plug 14 may be connected to the usual ignition circuit in parallel with one of the spark plugs of the engine, as indicated in the drawing, wherein 15 and 16 designate the wires of any usual or suitable ignition circuit, leading to an engine spark plug 17, said wires 15 and 16 being connected respectively to the electrodes of the spark plug 17. It will be understood that one of these circuit wires, for example, 15, is grounded to the engine as indicated at 18, and one of the electrodes of the spark plug 14 is also grounded in the usual manner, the other electrode being connected by wire 16 to the ignition circuit wire 16.

The operation is as follows: In starting the engine the throttle 11 is also slightly opened, so that there is a considerably greater condition of suction or vacuum on the side of the throttle toward the engine 85 than exists in the mixing chamber; hence, under these conditions a portion of the mixture is drawn from the mixing chamber through the tube 10 into the heating chamber 8 and thence through the tube 12 to the outlet 3, thereby charging the heating chamber with combustible mixture. When the engine is "turned over" in starting, current is sent through the spark plug, causing a spark within the heating chamber 95 for igniting the mixture therein. The tubes 10 and 12 are of sufficient length and with such small bore and thick walls of heat-conducting material as to prevent the ignition from being transmitted from the 100 heating chamber to the mixing chamber 4. The combustion of the charge in the heating chamber heats the walls of the outlet 3 and of the mixing chamber, so as to give an initial heating effect to the fuel and to 105 the mixture. The products of combustion are exhausted through the tube 12 and are in such minute quantities that they have no appreciable effect upon the carbureted mixture. The heating chamber 8 and the 110

tubes 10 and 12 are comparatively small. Therefore, the pulsating or back pressure while present is so small that it does not interfere with or nullify the action of the carbureter to any appreciable extent. Any such interference of nullification of the carbureter action, however, is compensated by the heated mixture which is drawn into the engine, such mixture being of greater combustible qualities, for reason of its being heated. In internal combustion engines it is desirable on account of price to use heavier fuels than gasolene, for example, kerosene and distillate, but the use of these heavy fuels is open to the objection that it is difficult to vaporize the same and to form an effective mixture with the air, particularly when the engine is cold as in starting. By the above described operation sufficient heat is imparted to the walls in contact with the mixture to insure vaporization of the fuel and effective mixture thereof with the air. It will be noted that as the throttle 11 is opened wider, condition of suction at the outlet 12 of the heating chamber approaches more closely to the condition within the mixing chamber so that relatively less charge is drawn through the heating chamber, therefore, after the engine has been started and the throttle is opened wider, less charge is drawn into the heating chamber and less heat is applied to the fuel and mixture, this being desirable for the reason that less heat is required under these conditions due to the fact that the carbureter is then receiving heat directly from the engine.

It will be noted that an advantage of the present invention is that the initial heating of the carburetor is not dependent upon heat from the engine, so that the engine may be started cold, whereas, in those carburetor heating systems depending upon the use of exhaust gases, the engine must be started before the heating action is effected. The method of heating by combustion of the mixture as above described is much more economical than where electric current is used directly for heating, the consumption of current in igniting the mixture being negligible with that which would be required to produce the heating effect maintained by combustion of a portion of the mixture as described.

55. What I claim is:

1. In combination with a carbureter provided with a mixing chamber and with an outlet therefrom for supplying mixture to an engine, a combustion chamber located in heating relation to said mixing chamber and communicating therewith to receive combustible mixture therefrom independently of the mixture passing through said outlet, and means for igniting the charge in said combustion chamber.

2. In combination with a carbureter, a heating chamber adjacent to the outlet of said carbureter to heat the mixture passing therethrough, means for supplying mixture from the carbureter to said heating chamber, means for igniting the mixture in said chamber, and means for discharging the products of combustion from said chamber to the outlet of the carbureter.

3. In combination with a carbureter provided with a mixing chamber and with an outlet, a combustion chamber adjacent to said mixing chamber to heat the same and communicating with said mixing chamber and also communicating with the outlet, a throttle located in the outlet between the points where the said combustion chamber communicates with the mixing chamber and with the outlet, and igniting means for the combustible in said combustion chamber.

4. In combination with a carbureter provided with a mixing chamber and with an outlet, a combustion chamber adjacent to said carbureter to heat the same, a conduit establishing communication from the mixing chamber to said combustion chamber, said conduit being restricted to prevent passage of flame therethrough, and igniting means in said combustion chamber.

5. In combination with a carbureter provided with a mixing chamber and an outlet, a combustion chamber adjacent said mixing chamber to heat the same and provided with a restricted communication with said combustion chamber and with a restricted communication with said outlet, a throttle in the outlet between the points of communication of the combustion chamber with the mixing chamber and outlet, and means for igniting the charge in said combustion chamber.

6. The combination of a carbureter provided with a mixing chamber and with an outlet, of a combustion chamber adjacent to and surrounding the outlet of the carbureter to heat the same, said chamber having an intake port to supply mixture from the mixing chamber to the combustion chamber and an outlet port communicating with the mixing chamber, said ports being relatively small, and means for igniting such mixture, said chamber being free from communication with the outlet except for relatively small ports such that will not allow propagation of ignition from the chamber into the outlet.

7. The combination with the ignition circuit of an internal combustion engine and a carbureter having an outlet connected with the engine to supply a combustible mixture thereto, of a combustion chamber located in heating relation to the outlet, said chamber having an intake port to supply mixture from the mixing chamber to the combustion chamber and an outlet port communicating

with the mixing chamber, said ports being relatively small, and electrical igniting means in the chamber connected with the ignition circuit, said chamber being free from

5 communication with the outlet except for relatively small ports such that will not allow propagation of ignition from the chamber into the outlet.

8. The combination with a carbureter
10 having an outlet for supplying a combustible mixture to an engine, of a combustion chamber located in heating relation to said

outlet, and communicating therewith to receive a combustible mixture therefrom, and means for igniting a charge in said combustion chamber. 15

In testimony whereof, I have hereunto set my hand at Los Angeles, California, this 23d day of August 1915.

ALFRED C. STEWART.
